UNITED STATES PATENT OFFICE.

FREDERICK W. LINAKER AND THEODORE M. BRUBACK, OF DUBOIS, PENNSYLVANIA.

SOOT CLEANER FOR BOILERS.

Application filed March 3, 1921. Serial No. 449,446.

This invention relates to soot cleaners for removing soot from boiler tubes or flues, by the injection of a jet or jets of steam or other cleaning fluid, steam being the most commonly used. As applied to water tube boilers, such soot cleaners commonly involve a movable tube or cleaner element, which is either built into the boiler or is insertable therein when required, and is commonly movable, either endwise or rotatively, or both, to direct the jet or jets of steam in various directions among the boiler tubes, for effectually blowing off the soot therefrom. As applied to boiler flues, the steam pipe or cleaner element is arranged either to blow a single jet into the flue at one end, or, in the case of large flues, it extends some distance within the flue, and has one or more jet nozzles directing jets of steam longitudinally of the flue. For either type of cleaner, it is customary to control the steam by a hand valve, to admit the steam to the cleaner element, or, in the case of multiple elements, to one such element at a time. In the use of such appliances, it has been found that steam at or above a certain pressure (which may vary with different types of apparatus) is required to effectively remove the soot; and that, when the steam pressure falls materially below such minimum, the cleaning becomes ineffective. In actual practice it is commonly found, especially where many jets are used simultaneously, that the operating pressure at the jets is reduced too low for efficient action. This can be corrected only by using fewer jets, or a larger supply pipe, both of which are disadvantageous. It is well recognized that the most efficient cleaning is accomplished with steam of high pressure and high superheat. To insure that the operation shall be performed under this condition is the aim of this invention.

The present invention provides automatic means for interrupted or intermittent cleaning or soot blowing, whereby a substantially ideal operation may be attained.

In practicing the invention, automatic means are provided for alternately turning on and off the steam leading to the cleaner element, or to the main pipe supplying multiple cleaner elements, as the case may be. To insure this intermittent operation, an intermediate vessel or receiver is provided, into which the steam from the boiler may

flow at an approximately uniform rate, and from which steam is discharged to the cleaner elements, and in which receiver the steam pressure may be subject to considerable fluctuations. The mechanism for intermittently operating the control valve may, in the preferred form of the apparatus, operate under control of the fluctuations of pressure in such receiver.

Figure 1 of the accompanying drawings is an elevation of a boiler to which soot cleaning devices, controlled according to the present invention, are applied, the particular type of boiler shown being a Babcock and Wilcox water tube boiler.

Fig. 2 is a sectional elevation, on a larger scale, showing the steam receiver and interrupter mechanism.

Fig. 3 is a section showing the automatic interrupter mechanism on a larger scale than is shown in Fig. 2.

Figs. 4 and 5 show a modified mechanism, the former being a section corresponding to Figs. 2 and 3; the latter an end elevation of Fig. 4.

Fig. 6 is a section on a still larger scale of a drain valve.

Referring to the drawings, it will be understood that Fig. 1 shows merely one of many applications of soot cleaners to which the present invention is suitable. It is well understood in this art that the particular type and arrangement of cleaner elements or steam nozzle pipes must be varied according to the kind or type of boiler used, and in many cases also according to special local conditions.

Taking, however, as an example, the arrangement shown in Fig. 1, and assuming that steam is used as the cleaning fluid, this steam enters by a supply pipe 8 and passes through the steam chamber or receiver 9 and interrupter mechanism 10 into the header or main pipe 12, and thence, through branch pipes or risers 7, 7, to the respective cleaner elements which, in the present example, are numbered 1, 2, 3, 4 and 5. The cleaner elements shown are of the rotary type, that is, a steam pipe passes transversely across the furnace chamber above, below, or among the boiler tubes, and is mounted to be rotated so that the steam from its jet orifices may be projected at varying angles between the tubes. For this purpose, when the elements are too high to be easily reached, it is customary to provide a sheave wheel

turned by hand through a pendent chain 6; in the case of an element like that shown at 4, which is low enough to be within reach, a hand-wheel is used for turning it. Each 5 branch pipe 7 is controlled by a hand valve 11 and usually, during the operation of soot cleaning, only one control valve 11 is open at a time, so as to blow steam through only one of the soot cleaner elements.

10 The steam from admission pipe 8 enters directly into receiver 9 and flows thence through the interrupter 10 under intermittent control of a valve 13 which is opened and closed at suitable intervals of time, by 15 means which will be described presently.

The steam enters freely through opening 14 from the receiver to the inlet valve chamber, and thence flows from the outlet valve chamber 15 to the header 12.

20 The function of the interrupter is to check the flow of steam to the cleaner element when the pressure in the receiver is dropped to a pre-determined minimum; and to restore the flow of steam when the pressure in the receiver has risen again to the boiler pressure or to a pre-determined approach thereto. It has been found in practice that the average pressure throughout the length of the cleaner 25 elements while in operation is approximately

30 half or less, and in some cases only one-fourth of the boiler pressure available for cleaning purposes. It is well known that the higher the steam pressure and superheat that can be supplied to the jet nozzles or 35 orifices of the cleaning elements, the more efficient and the quicker will be the cleaning action. Heretofore, this has in many cases been attainable only by using large sized pipes between the source of steam and the 40 cleaner element, which makes the apparatus expensive.

According to the present invention, the receiver 9 is introduced between the steam supply and the cleaner elements, or the 45 header 12 distributing the steam to such elements, and has a capacity which is suitably proportioned to the particular requirements of the cleaner apparatus. When the outflow valve 13 is closed and the admission valve 50 to the receiver 9 is open, the pressure in the receiver rises to the pressure of the steam supply. When any distributing valve 11 is open and the valve 13 opens, the steam flows from the receiver to the cleaner element, the 55 outflow from the receiver being at a rate more rapid than the inflow thereto, so that the pressure in the receiver falls. When this pressure has decreased to a predetermined point, as for example 25 or 30 per 60 cent of the boiler pressure, the interrupter mechanism operates to close the valve 13, whereby steam is temporarily cut off from the cleaner element, while the boiler continues to supply steam to the receiver, whereby 65 the pressure in the latter can raise to, or

nearly to, boiler pressure; on the latter pressure, or any determined maximum pressure being reached in the receiver, the valve 13 may be reopened, permitting the further outflow of steam to the cleaner element. 70 This intermittent opening and closing of the valve 13 is repeated as long as the distributing valve 11 to any element is kept open.

The particular interrupter mechanism will now be described, taking up first the 75 pressure control mechanism shown in Fig. 3: In this construction, the interrupter valve 13 is operated under control of pressure actuated pistons in such manner that, when the pressure in the receiver falls to a determined 80 minimum, the valve 13 is closed; and when such pressure rises to a determined maximum, the valve 13 is opened. Thus, the operation of the valve 13 is controlled wholly by the differences in pressure, and 85 without regard to intervals of time. Obviously, various pressure-controlled means may be provided for thus operating the valve 13, the particular means for this purpose which is shown being given only as 90 one example.

This particular mechanism comprises three plungers 16, 17 and 18, exposed on their under sides to the steam chamber 22, which is in free communication, through 95 opening 14 with the receiver, and receiving on their upper sides the downward pressure of springs marked respectively 160, 170 and 180. These springs react upwardly against screw plugs 161, 171 and 181, respectively, 100 by which the spring stresses may be adjusted if required. The plugs have vents 28. The size and compression of spring 180 is such that plunger 18 can be lifted only by the maximum steam pressure in chamber 22, 105 (for example, 100 per cent of the boiler pressure). The spring 170 affords such pressure that plunger 17 will lift when a certain lower pressure (for example, 75 per cent of the boiler pressure) exists in chamber 22. 110 Spring 160 has such pressure that plunger 16 may be lifted by the minimum steam pressure (for example, 50 per cent of the boiler pressure). Each plunger has a peripheral groove 19, the three grooves being 115 located at different levels; balls 20 and 21 are located in transverse openings in the cylinder walls between the respective plungers, at appropriate levels, each ball being of such size that when the grooved portion of one plunger coincides with it and it is against the ungrooved portion of the other plunger, it cannot escape from such grooved portion, and, consequently, holds fixedly in position the plunger whose groove it engages. 120 In the position shown in Fig. 3, the balls 20 and 21 are thus locking fast the plungers 17 and 16, the valve 13 is closed, and the plunger 18 is free or unlocked. Thus, while the steam pressure is rising from the min- 125

130

imum to the maximum, it cannot lift plungers 16 or 17 until, on reaching the maximum, it lifts plunger 18, whereupon the groove 19 of this plunger, on rising to the level of ball 20, permits this ball to shift laterally into such groove and out of the groove of plunger 17, which is accordingly unlocked, and, as the pressure beneath it exceeds the resistance of spring 170, this plunger immediately rises; on its groove 19 reaching the level of ball 21, the latter ball likewise shifts laterally into such groove and thereby unlocks plunger 16, which also immediately rises, because the steam pressure beneath it is in excess of the pressure of spring 160. The lifting of plunger 17, which is connected to valve 13 by stem 130, lifts the valve and permits the outflow of steam from the receiver to the header 12 and cleaner element. Such outflow continues until the steam pressure in 22 falls to the minimum because plungers 18 and 17 are locked in their upper positions and cannot be forced down by their springs until plunger 16 is first caused to descend, which occurs only when the steam pressure falls low enough to enable the weaker spring 160 to act. Thereupon, as plunger 16 falls to its position shown, the ball 21 shifts laterally into its groove, thus unlocking plunger 17, which is instantly pressed down by its spring, in turn permitting ball 20 to resume the position shown, and unlock plunger 18, which also descends. The descent of plunger 17 closes valve 13 and stops the outflow of steam, permitting the pressure in the receiver to again rise. This intermittent operation continues as long as any distributing or control valve 11 remains open.

The movements of the pistons, as they are successively unlocked, would be very abrupt, so that the valve 13 would seat with considerable shock, if some means were not provided for cushioning its movement. For this purpose, a dash pot 23 is provided, shown as a plunger connected to the valve and working in a cylinder chamber beneath, this chamber 25 below the plunger being vented, through a small bore 24, into a chamber 26 on the under side of the valve. Through the valve is a vent duct 27 to balance the pressure in the chamber 26 with that in chamber 22. This dash pot device cushions both movements of the valve. Similar dash pots may be provided for cushioning the movements of the plungers 16 and 18. Such cushioning means are not shown, but the plungers are shown provided with prolonged stems 30, 31, which serve as stops to limit their movements. For draining condensation from the chamber 26 an automatic drain valve 28 is provided, the construction of which is shown in Fig. 6. A similar drain valve may be applied at 28' beneath the receiver 9. When there is steam pressure in the chamber 26 or

receiver 9, the ball of the drain valve is forced to its seat and closes the opening; when the pressure is removed, the ball falls and water can drain out.

The interrupter shown in Figs. 4 and 5 operates the valve 13 mechanically and independently of the pressures in the receiver 9. The inlet 14 from the receiver admits steam beneath the valve 13 and, when the valve is lifted, the steam escapes through chamber 15, to the pipe 12. The valve is operated intermittently by cam mechanism or other intermediary from any convenient source of power, that shown being an electric motor 35, which drives a gear wheel 36 having a cam 37 which operates a lever 38, the short arm of which is connected, by a link 39, to the valve rod 40, which passes through suitable stuffing boxes and receives the downward pressure of a spring 41 to close the valve. The motor (or other source of power) will rotate at a constant speed, and hence the valve will be opened and closed at regular intervals of time. When this type of mechanism is used, it is necessary to determine the conditions required for the specific installation, and to so proportion the speed of the wheel 36 and length of the cam 37 as to afford the proper timing so as, on the one hand to permit the discharge of steam through the cleaner element long enough each time to perform the cleaning operation, and then afford sufficient time for building up the required maximum pressure in the receiver. These conditions can be varied by changing the speed of rotation of the motor, or by changing the gearing down ratio, or by varying the length of the cam segment 37.

The two interrupter mechanisms shown are given by way of examples, it being understood that the invention may be otherwise applied, depending upon the conditions presented in any specific instance, such as the boiler pressure, the discharge capacity of the cleaner nozzles, the capacity of the receiver, and the source of power most conveniently available for operating the interrupter. It is to be understood that the construction in any case may be varied to any desired extent, within the scope of the appended claims.

What is claimed is:-

1. The combination of a soot cleaner, a source of cleaning fluid under pressure, an interposed receiver, a pipe leading from said source to the receiver, and an interrupter controlling the flow of fluid from the receiver to the cleaner, having means for intermittently operating the interrupter to hold it open to blow out the major part of the contents of the receiver through the cleaner, and then to close it and hold it closed long enough to permit the receiver to refill to normal pressure.

2. Apparatus according to claim 1, the means for intermittently operating the interrupter being pressure-operated.
3. The combination with a soot cleaner and a source of fluid under pressure, of an intervening receiver, a pipe leading from said source to the receiver, and an interrupter at the outlet from the receiver to the cleaner for intermitting the flow from the receiver to the cleaner, comprising a valve and means actuated by the variations of pressure in the receiver adapted to open said valve at a prescribed maximum pressure and to close it at a prescribed minimum pressure.
4. Apparatus according to claim 3, the pressure actuated means comprising spring-pressed plungers, the one movable under a maximum pressure and the other under a minimum pressure, and means for communicating their alternate movements to the valve.
5. Apparatus according to claim 3, the pressure actuated means comprising three spring-pressed plungers responding respectively to minimum, intermediate and maximum pressures, the intermediate plunger connected to actuate said valve, and connections between the minimum and maximum plungers for controlling the movements of the valve, to open it upon the maximum pressure and close it upon the minimum pressure.

In witness whereof, we have hereunto signed our names.

FREDERICK W. LINAKER.
THEODORE M. BRUBACK.
